UNITED STATES PATENT OFFICE.

VICTOR VJECHA, OF CLEVELAND, OHIO.

CONVEYING AND DISCHARGING APPARATUS.

Specification of Letters Patent. Patented Oct. 19, 1915.

1,157,466.

Application filed May 29, 1914. Serial No. 841,739.

To all whom it may concern:

Be it known that I, VICTOR VJECHA, a subject of the Emperor of Austria-Hungary, resident of Cleveland, county of Cuyahoga, and State of Ohio, have invented a new and useful Improvement in Conveying and Discharging Apparatus, of which the following is a specification, the principle of the invention being herein explained and the best mode in which I have contemplated applying that principle, so as to distinguish it from other inventions.

My invention relates to conveying and discharging apparatus, its object being to provide means for use in shops or factories whereby a plurality of objects such as castings or the like may be conveyed from place to place and discharged in a manner such as to distribute same over a comparatively large area, thereby avoiding the necessity of dumping same into one single pile.

The said invention consists of means hereinafter fully described and particularly set forth in the claims.

The annexed drawings and the following description set forth in detail certain means embodying my invention, the disclosed means, however, constituting but one of various mechanical forms in which the principle of the invention may be applied.

In said annexed drawings: Figure 1 represents a vertical, central, transverse section of a device embodying my invention in which the parts are shown in their conveying position. Fig. 2 represents a section similar to that shown in Fig. 1 in which the parts are shown in their discharging position. Fig. 3 represents a vertical, longitudinal section taken upon the plane indicated by line III—III in Fig. 1. Fig. 4 represents a front elevation of a fragmentary portion of the device, illustrating detail parts and shown upon an enlarged scale. Fig. 5 represents a side elevation of the parts shown in Fig. 4. Fig. 6 represents a side elevation of detail parts of the device upon the said same enlarged scale. Fig. 7 represents a horizontal section taken upon a plane indicated by line VII—VII in Fig. 6.

The illustrated embodiment of my invention comprises a frame 1 including in its structure two pairs of side bars 2, 2, converging upwardly and joined at the top by means of an upper cross bar 3. Secured to each side bar 2 is a downwardly extending

vertical bar 4 which terminates in the horizontal plane in which the side bars 2, 2, terminate. Each oppositely disposed pair of bars 2, 2, and 4, 4, carries at their lower ends a journal rod 5, Fig. 1, which support the floor of the conveyer. This floor consists of a plurality of rectangular sections 6 each of which is tiltably mounted upon one of said bars 5, bearing members 7 being secured upon the bottom of each such section through which the said rods pass. Articulating with the side of each such section and in a vertical longitudinal plane which intersects each section intermediately of the axis of the corresponding rod 5 and the central longitudinal plane of the device, are tilting or connecting rods 8, there being a set of four of these rods on each side of the device. The upper ends of each of these four connecting rods articulate with a strap 9, which is provided with a lug 10 formed with a guiding groove 11 into which projects a vertical guiding strip 12 secured to the inner face of the vertical central member 13 forming a part of the frame. The lower portion of this vertical central member 13 is braced by means of a cross-piece 14 whose ends are respectively secured to the corresponding inclined side bars 2, 2, as shown in Figs. 1 and 2. The said strap is formed with a central bore in which is rotatably mounted a nut 14^a having an upper and a lower cylindrical flange 15 and 16 respectively, these flanges preventing longitudinal movement of the nut in said strap. This nut is mounted upon a vertical screw 17, the upper end of which is journaled in a bearing member 18 suitably secured to the member 13 of the frame and the lower end of which is journaled in a bearing member 19 suitably secured to the cross-piece 14. The upper end of said screw has secured thereto a bevel pinion 20 which meshes with a second pinion 21 secured to a horizontal shaft 22 whose ends are mounted in suitable bearing members 23 secured to the inner face of the corresponding vertical frame member 13, as shown in Figs. 4 and 5. One end of this shaft is provided with a gear 24 which meshes with a pinion 25 secured to the shaft of an electric motor 26 mounted upon a bracket 27 suitably secured to the frame. A suitable switch 28 is provided in a convenient place for starting and stopping said motor.

The upper flange 15 is provided with a ratchet tooth 29 which is normally engaged by a spring-actuated pawl 30 oscillatory mounted upon the strap 9, as shown in Fig. 5. This pawl therefore holds the said nut against rotation with the screw when the latter is rotated, the inclination of the ratchet tooth being so arranged that it will pass the pawl when the rotation of the screw 10 and hence of the nut is in one direction and will engage and prevent such rotation when the screw is rotated in the opposite direction. In the device illustrated such non-rotation will be effected when the screw is turned in the direction indicated by the arrow in Fig. 4 and rotation will be permitted when rotation is in the opposite direction, as will be readily understood. On the opposite side of the strap is a second pawl 31 15 which similarly engages a ratchet tooth 32 formed in the circumference of the lower flange 16, as shown in Fig. 5. This tooth has the opposite direction of inclination and the pawl 31 therefore permits rotation of the nut when the screw is rotated in the direction of the arrow in Fig. 4 and prevents rotation of such nut when the rotation of the screw is in the opposite direction. Near the upper end of the screw and secured to the frame is an arm 33, Figs. 4 20 and 5, which lies in the path of travel of the outer arm of the pawl 30. At a suitable point below said arm 33 is similarly secured a second arm 34 which lies in the path of travel of the pawl 31. It will therefore be seen that when the nut and strap reach a point near the upper end of their path of movement, the pawl 30 will be caused to disengage the nut and permit its rotation 25 with the screw 17. Similarly when the said points reach a lower point in their travel, the pawl 31 will be caused to disengage the nut and permit its rotation in the opposite direction with said screw. During such movement the guiding-strip 12 maintains the proper rigidity of the strap 9.

When the nut and strap are in their uppermost position, as shown in Fig. 1, the floor sections all occupy a horizontal position. In this position the device may be loaded with the articles which it is desired to transport and later discharge. For the purpose of permitting the device to be readily loaded, end-walls 35 are provided which may be tilted downwardly and afford runways from the floor of the shop to the floor of the device in order to permit trucks to be readily moved thereupon. The floor sections may also be provided with side-pieces 36 which prevent the articles which are being transported from falling off. During such transportation the end swinging walls 35 may be tilted upwardly and latched to serve a similar purpose. The device is suspended by means of a chain 37 from a suit-

able crane or trolley whereby it may be carried from one part of the shop to another.

When the loaded carrier reaches a point at which it is desired to discharge its contents, the motor 26 is operated to rotate the shaft 22 in a direction such as will cause the screw 17 to rotate in the direction opposite that indicated by the arrow, both screws being, as shown in the drawing, 70 right-hand and being rotated in the same direction, rotation of the shaft 22 in such case being opposite that indicated by the arrow in Fig. 4. At the beginning of this rotation the nut 14 will rotate until the 75 ratchet tooth of the lower flange 16 engages the pawl 31 whereupon its rotation will cease and the nut will then be caused to travel downwardly on the screw. This action will cause the connecting rods 8 to 80 push downwardly upon the inner ends of the sections 6 of the floor and tilt same, as shown in Fig. 2. This rotation is continued until the nut reaches a position in the lower portion of its travel in which the arm 34 85 will engage the pawl 31 and disengage the same from the ratchet tooth in the lower flange 16. A continued rotation of the screw will therefore permit the nut to rotate with it and the further downward movement 90 thereof is thus stopped. When this point is reached the sections 6 will have reached a position in which the inclination thereof is sufficient to discharge all of the articles 95 previously carried thereby. As will be 100 noted, such discharge takes place at three different places and the articles are thus distributed in these three places instead of in one place as it has heretofore been the custom. The parts being in the position last 105 described, the opposite rotation of the shaft 22, that is in the direction indicated by the arrow in Fig. 4, will impart to said nut a partial rotation until the pawl 30 engages the upper ratchet tooth. Further rotation 110 of the screw will therefore cause this nut to travel upwardly until it reaches its uppermost position. Just before reaching the latter the arm 33 will engage the said pawl 30 and disengage it from the upper ratchet 115 tooth, thus permitting the nut to rotate and causing a cessation of every upward movement thereof. At this point the floor sections will have reached their horizontal position, as shown in Fig. 1, when it will be 120 again ready for loading.

Having fully described my invention, what I claim and desire to secure by Letters Patent is:—

1. In apparatus of the class described, the 125 combination of a frame; a supporting floor tiltably mounted upon said frame; a screw rotatably mounted upon the latter; a rotatably-stationary nut mounted upon said screw; arms connecting said nut with said 130

floor; and means for rotating said screw whereby said nut may be caused to move and tilt said floor.

2. In apparatus of the class described, the combination of a frame; a supporting floor tiltably mounted upon said frame; a screw rotatably mounted upon the latter; a rotatably-stationary nut mounted upon said screw; arms connecting said nut with said floor; means for rotating said screw whereby said nut may be caused to move and floor tilt; and means for rendering said nut rotatable with said screw at predetermined positions in its travel.

3. In apparatus of the class described, the combination of a frame; a rotatable screw mounted upon said frame; a nut mounted upon said screw; means for non-rotatably holding said nut; and means located in the path of travel of said nut along said screw adapted to actuate said holding means to release said nut whereby the latter is rendered rotatable.

4. In apparatus of the class described, the combination of a frame; a rotatable screw mounted upon said frame; a nut mounted upon said screw and provided with a circumferentially located ratchet tooth; a strap

mounted upon said nut in which the latter is rotatably mounted; a spring-actuated pawl normally engaging said ratchet tooth and mounted upon said strap; and an arm fixed to said frame and lying in the path of movement of said pawl, whereby the latter may be actuated to disengage the said nut and permit the latter to rotate in said strap.

5. In apparatus of the class described, the combination of a frame; a rotatable screw mounted upon the latter; a nut mounted upon said screw; a strap mounted upon the said nut in which the latter is rotatable; a spring-actuated pawl engaging a ratchet tooth formed on the circumference of said nut; a guiding strip parallel with said screw and secured to said frame; a guiding-groove in said strap into which said guiding strip projects; and an arm projecting into the path of movement of said pawl adapted to actuate the latter to disengage said ratchet tooth.

Signed by me, this 27th day of May, 1914.

VICTOR VJECHA.
